HARVEY HUBBELL, OF BRIDGEPORT, CONNECTICUT; LOUIE E. HUBBELL EXECUTRIX
OF SAID HARVEY HUBBELL, DECEASED

PLUG RECEPTACLE

Application filed November 8, 1927. Serial No. 231,847.

This invention relates to plug receptacles for attachment plug caps and has for an object to provide a simple and easily assembled structure which will require the minimum amount of expensive insulating material.

Certain of the composition materials used for molding insulating bodies for this type of article are of relatively low cost, but some of the newer phenolic condensation products, such as bakelite, make stronger and more attractive looking plugs, but this material is relatively quite expensive. I have, therefore, devised a plug receptacle in which the amount of insulating material required for each plug is greatly reduced over the type of plugs ordinarily in general use and I can, therefore, effect a material saving in the amount of material used, especially where the plugs are made in quantities, and can thus make the caps of better material without increasing their cost to the consumer.

With the foregoing and other objects in view, I have devised the construction illustrated in the accompanying drawing forming a part of this specification. In this drawing,

Fig. 1 is a longitudinal section through the plug receptacle substantially on line 1—1 of Fig. 2.

Fig. 2 is a side elevation thereof.

Fig. 3 is a transverse section substantially on line 3—3 of Fig. 1.

Fig. 4 is an end elevation of the screw shell contact.

Fig. 5 is a side elevation of the insulating body member but showing the contact securing rivet in position, and

Fig. 6 is an end elevation thereof looking from the bottom of Fig. 5.

My improved plug receptacle includes the insulating body member 10 having longitudinally extending passages 11 and 12 in which are placed the spring contacts 13 and 14 respectively. These passages also open through the front wall of the body for insertion of the contact blades of an attachment plug cap, not shown. For use in the standard screw shell sockets the inner edge of the flange 15 of the body must be a given distance from the tip or central contact 16 in order to make the proper contacts in the sockets

and give the proper clearances. In the plugs as now generally constructed the central contact is mounted on the inner end of the body and only projects a short distance therefrom, and the screw shell contact forming the other electrical contact is also mounted at the inner end of the body only a short distance backwardly from the central contact. This requires a relatively long insulating body and requires considerable insulating material. In the present device, however, I have devised a construction whereby the central contact may project a considerable distance from the inner end of the body and have shifted the screw shell contact backwardly away from the central contact so that I can materially shorten the insulating body, thus effecting quite a considerable saving in the amount of insulating material required. I have also devised a means whereby the contacts can be mounted on a post projecting from the inner end of the body so that the outer walls of the body can be still further shortened effecting a still further saving in the amount of material required.

Referring to the drawing the body 10 has a central post 17 projecting from its inner end and secured in this post, preferably by molding it into the material, is a securing element 18, in the present construction in the form of a hollow rivet which as shown projects a considerable distance from the inner end of the post. This post is provided with shoulders 19 spaced inwardly somewhat toward the body of the cap from the end of the post, and I mount on one of these shoulders the screw shell contact 20. This element is of general cup shape threaded on its outer wall, as shown at 21, to screw into the screw shell contact in the lamp or other socket and form a second electrical contact, and at its closed end is provided with an opening 22 having a substantially rectangular section 23 in the side thereof to receive the similarly shaped projecting end portion 24 of post 17 of the body member, and therefore, the end wall of this screw shell seats on one of the shoulders 19, as shown in Fig. 1. As this shell is firmly mounted on this post and secured to this shoulder as will be more fully described

later, it is not necessary to extend the outer wall of the body to the inner end of this shell as in the old constructions. The outer walls of the body are, therefore, shortened so as to extend only a short distance into the open end of the screw shell, as shown at 25. It will be obvious this arrangement effects a considerable saving in the amount of material required, while the end of the body is sufficiently 5 embraced by the walls of the screw shell so that the shell is rigidly held in the proper position. The end of the shell also has a slot 10 through which the angular end portion 15 of the contact 13 may project, and it seats on the outer side of this end wall against which it is held to provide good electrical contact by pressure from the insulating disc 28.

The other contact 14 extends through the disc 28 and has a laterally extending foot 29 resting against the end of post 17, and it is preferred that this foot be perforated for passage of the securing rivet 18. Mounted on the rivet and embracing the projecting portion thereof is a metal sleeve 30, and its inner end is preferably flanged so as to provide a good contact for the foot 29. Enclosing this sleeve is a central member 31 which is preferably substantially conical with its base resting against the disc 28 and its smaller end embracing the rivet and engaging the outer end of the sleeve 30. If now the free end of the rivet 18 is spun over or riveted over as shown at 32, it will secure all the elements in position on the body. It will press the conical member 31 against the disc 28 and clamp the screw shell 20 against the shoulder on the central post 17 and it will also form a good tight contact between the angular end 27 of the contact 13 and the screw shell. The riveting over of the head of the rivet also presses the member 31 against the end of the sleeve 30 and clamps the base of this sleeve against the foot 29 and contact 14. It, therefore, clamps this foot against the end 40 of the post besides providing a good electrical contact between this contact and the sleeve and between the sleeve and the central contact and the rivet. Therefore, the single operation of spinning over or riveting over the head of the rivet clamps all the elements in position on the body and provides the required electrical contact between the various elements. As this sleeve 30 permits the extension of the central contact a considerable 50 distance beyond the end of the body member this body member can be materially shortened over the old structure, and therefore, this effects another material change in the amount of material required for the body member. Before assembling the angle between the body of the contact 14 and the foot 29 is greater than a right angle so that when the securing rivet is set and the foot clamped against the end of the post the contact will be placed under some tension and

its free end held thereby against the side of its passage. The same is true on contact 13 except that here the angle should be less than a right angle. On the opposite sides of the post 17 between the passages 11 and 12 sockets or chambers 33 may be provided to still further reduce the amount of material used in the body. I have, therefore, provided a structure which greatly reduces the amount of material required for the body member, and have done this without increasing the assembling operations over what are required in the old types of these devices.

Having thus set forth the nature of my invention, what I claim is:

1. In a plug receptacle, an insulating body member having longitudinal passages for contact blades and a central post extending beyond its inner end provided with a shoulder adjacent its free end, a securing rivet secured in the end of the post, a screw shell contact resting on said shoulder and extending to and embracing the inner end of the body member, a spring contact electrically connected with the screw shell and extending into one of said passages, a central contact secured to the post by said rivet, and a second spring contact in the other passage and electrically connected with the central contact.

2. In a plug receptacle, an insulating body member having longitudinal passages for contact blades and a central post extending beyond its inner end, a screw shell contact mounted on said post adjacent its free end and extending to and embracing the inner end of the body, a contact in one of the passages and connected to said shell, a rivet secured in the end of the post and projecting therefrom, a contact in the other passage and having an extension resting on the end of the post, a sleeve embracing the rivet and engaging said extension at one end, and a central contact engaging the other end of the sleeve, said rivet serving to secure the central contact and press the sleeve against the extension to form an electrical connection between the central contact and the contact in the second passage.

3. In a plug receptacle, an insulating body member having longitudinal passages for contact blades and a central post projecting from its inner end, a securing rivet projecting from the inner end of the post, a contact in one of the passages having a perforated foot to receive said rivet and resting against the end of the post, a metal sleeve embracing the rivet and engaging said foot, and the free end of the rivet being turned over to press the sleeve against the foot and clamp it against the post.

4. In a plug receptacle, an insulating body member having longitudinal passages for contact blades and a central post projecting from its inner end having a shoulder adja-

cent its free end, a screw shell resting on said shoulder and extending to embrace the inner end of the body, a contact in one of the passages extending through the end of the screw shell and having an end portion engaging the outer surface of said shell, an insulating disc on the outer side of said end wall, a securing rivet extending from the end of the post, a contact in the other passage having a foot 10 provided with an opening for said rivet and resting against the end of the post, a metal sleeve on the post engaging said rivet, a central contact resting at its base on said disc and having an opening to receive said rivet, 15 and the end of the rivet being turned over to clamp said elements to each other and to the body.

5. In a plug receptacle, an insulating body having longitudinal passages for contact 20 blades, a screw shell contact mounted on said body, a contact in one of the passages connected to said shell, an insulating disc engaging the inner end of the shell, a rivet secured in the inner end of the body and projecting therefrom, a contact in the other passage having an extension resting against the end of the body, a sleeve embracing said rivet and engaging said extension at one end, and a substantially conical member engaging 25 said sleeve at the other end and resting at its base on the insulating disc, the free end of the rivet being turned over against said member to secure the contacts and said member to the body.

30 35 In testimony whereof I affix my signature
HARVEY HUBBELL.
